UNITED STATES PATENT OFFICE.

FREDERICK H. KNAPP, OF WESTMINSTER, MARYLAND, ASSIGNOR TO THE FRED. H. KNAPP COMPANY, OF WESTMINSTER, MARYLAND, A CORPORATION OF MARYLAND.

LABELING-MACHINE.

1,091,850.

Specification of Letters Patent. Patented Mar. 31, 1914.

Application filed August 25, 1910. Serial No. 578,876.

To all whom it may concern:

Be it known that I, FREDERICK H. KNAPP, a citizen of the United States, residing at Westminster, in the county of Carroll and 5 State of Maryland, have invented certain new and useful Improvements in Labeling Machines, of which the following is a specification, reference being had therein to the accompanying drawing.

10 This invention relates to labeling machines, that is machines designed to apply to cans, boxes, or other packages a suitable label.

The invention is designed more particularly for applying labels to the body of the packages as the latter progress through the machine, conveniently by rolling action along a suitable runway.

For uniformity in terminology throughout the description and claims the articles to be labeled will be conveniently referred to as a can, though of course it is to be borne in mind that the machine is equally designed for use in the application of labels upon 25 various packages other than cans.

One of the important features of the invention resides in the provision of an improved form of pasting apparatus which, while susceptible of other adaptations, is 30 primarily intended for applying paste to what is known in the art as the lap end of the label, being the free end of the label which overlies the other end thereof previously affixed to the can.

35 The invention also comprises instrumentalities for adapting the pasting mechanism just referred to, to labels of different lengths, and to this end the pasting mechanism is adjustable in a novel manner longitudinally 40 of the machine.

The invention also includes a paste applying member for playing over the surface of the label, one which may be readily removed from the machine, and will take up 45 but a minimum amount of space, and which to a large extent, will reduce the traveling area of the paste applying member, and obviate the objectionable feature of daubing or smearing various parts of the machine 50 with paste.

The invention further contemplates an improved method of application for the paste pot or receptacle and the pasting mechanism carried thereby for the lap end 55 of the label, the parts being of a construc-

tion and arrangement permitting the receptacle, together with the pasting member and driving mechanism mounted thereon to be bodily removed as a unit from the machine, and preferably from the front side of the 60 machine.

Further the invention includes means whereby the paste applying member for the lap end of the label will have a constant and uniform pressure upon the various labels as 65 they are successively fed into position to be acted upon by the paste applying member.

Again the invention includes a novel form of curling device for the labels, one which will adapt itself to the labels, and which is 70 designed to be carried by the support for the paste applying member for the lap end of the labels, and to be adjusted with the latter.

The invention embraces a paste carrying belt adapted to project across the runway 75 and apply paste to the labels, and a swinging support for said belt, and for the curling device, which also projects across the runway above the labels and is automatically adjustable, said swinging support being 80 designed to permit the paste carrying belt and curling device to swing about a pivotal connection and fall by gravity into contact with the labels, and maintain a constant and uniform pressure upon the various labels, a 85 counterbalancing device being provided for said support, the same tending to regulate the pressure on the labels.

Further the invention comprises novel details in the construction and arrangement of 90 the various parts of the machine, to be more particularly referred to hereinafter, and for a clear understanding of the description to follow reference is respectfully directed to the accompanying drawings forming a part 95 hereof and wherein is disclosed, for the purpose of illustration, a convenient and satisfactory embodiment of the invention.

In the drawings: Figure 1 is a front elevation of the machine, Fig. 2 is a transverse 100 sectional view on line 2—2 of Fig. 1 looking in the direction of the arrow, Fig. 3 is a plan view of the label receptacle and the pasting mechanism for the lap end of the label associated therewith, Fig. 4 is a side elevation of 105 the pasting mechanism for the lap end of the labels the paste receptacle being shown in section, Fig. 5 is a detail plan view of the outer end of the overhanging bracket or support for the paste applying member, Fig. 110

6 is a detail elevation partly in section of the paste mechanism for the lap end of the labels and associated drive mechanism, Fig. 7 is a detail plan view partly in section of a 5 portion of the frame with the swinging support for the pasting mechanism for the lap end of the labels, Fig. 8 is a detail perspective view of the supporting arm or bracket for the paste carrier with the curling device for the labels carried thereby, Fig. 9 is 10 a detail view of the pressure regulator means, for the lap end of the paste belt; Figs. 10, 11 and 12 are detail views of parts removed.

Referring now more particularly to the 15 drawings wherein like reference characters designate corresponding parts throughout the several views 1 is the main frame, conveniently of metal and of substantially rectangular construction, the same being supported in any desired manner as by leg supports 2 which latter have at their lower ends anti-friction rollers 3, whereby the machine may be shifted from place to place as desired. A reinforcing element 4 extends 20 between and connects with the leg supports 2, and together with said legs constitutes a substantial and firm support for the frame work of the machine. Supported upon the frame 1 in any desired manner as by bracket supports 5 are runways 6 of any 25 desired construction, and the same being designed to support the body of the cans in position to be acted upon by the pasting and labeling appliances, as the cans are fed along the runway by suitable feeding mechanism, which in the construction illustrated 30 is shown in the form of endless belts or carriers 7. The said belts 7 are mounted upon pulleys 8 and 8^a, the pulley 8 being carried by a shaft 9 suitably journaled in an 35 upright support or supports 10 secured to the frame 1 in any desired manner. Also mounted upon the shaft 9 is a suitable driving pulley 11 adapted to receive movement from any suitable driving power not shown but 40 which may be conveniently a motor actuating device suitably affixed to the frame work of the machine. The pulley 8^a of course receives its motion through the medium of the belt 7 and said pulley is mounted upon a shaft 12 in turn journaled in bearings in 45 upright brackets or supports 13 secured to the frame work 1 of the machine in any desired manner. Connecting with the forward 50 end of the runway 6 is a feed or inlet chute for the cans to be labeled, it being borne in mind that suitable spacing mechanism of any of the approved types may be used at the forward end of the machine and 55 adjacent the chute 14, for timing and delivering of the cans to the runway 6, whereby they will be separated from one another a sufficient distance while being acted upon by the various instrumentalities of the machine.

60 Adjacent the outer or delivery end of the

machine is a delivery chute 15, the same being designed to deliver the labeled can from the machine to any convenient place of deposit. Adjacent the forward end of the machine and below the runway is mounted 70 a suitable paste receptacle 16, the same being of any convenient design and suitably mounted for detachment when desired from a support 17, which latter is secured in any desired manner as by connected arms 18 75 secured to the frame work 1. The paste receptacle is held in position upon the support 17 conveniently by threaded stems 19 engaging the support 17 and receptacle 16 respectively, said stems terminating in hand 80 wheels 20. Mounted within the receptacle for rotary movement are pasting members adapted to apply a coating of paste to the can at the junction of the body of the can with the flange of the can cap or lid and entirely around the circumference thereof, and also to apply a daub of paste of limited width extending substantially from end to end of the can. These pasting appliances are shown for convenience as comprising the 85 following parts: A felt covered roll 21 extends longitudinally of the receptacle 16, and longitudinally of the runway the same being mounted in suitable bearings and positioned so as to take up paste from the receptacle 16 and apply the same to the can at the junction of the flange of the lid and the can body, and entirely around the can. A transversely arranged paste applying roll 22 also conveniently having a felt tread is 90 arranged to take up paste from the receptacle 16 and apply a daub thereof to the can, extending substantially from end to end of the latter. The purpose of the paste applying roll 22 is to provide the can, as it passes along the runway 6 with a coating of paste 95 designed in the further movement of the can along the runway to engage with the forward end of a suitably supported label whereby to pick up the same and cause the 100 label to wind about the can. The purpose of the paste applying roller 21 is to cause, by the application of the label at the pasted portion of the can at the junction of the flange of the top and can body, a sealed joint 105 between the body of the can and the top thereof, to protect the contained goods from outside influences, and at the same time to leave substantially the entire body portion 110 of the label free from connection. A suitably supported shaft 23 is adapted for rotary movement through the medium of gear connection, conveniently as shown, with the shaft 12 of the feeding belt pulley 8^a, said shaft 23 conveniently having a worm 115 120 adapted to engage a worm gear 25 mounted on a projecting end of the shaft 26 of the paste roll 22, whereby the latter is rotated. The paste roll 21 has a gear connection not shown, with the shaft 25 whereby the paste 125 130

rolls 21 and 22 are simultaneously operated. A label receptacle 30 is positioned rearwardly of the receptacle 16, and is open at its top as usual for the reception of a supply of labels to be applied to the cans as the latter are fed along the runway. It is understood of course that the labels are supported upon a suitable follower 31 adapted to be raised at suitable intervals so as to position the uppermost label to be engaged by the can.

The actuating mechanism for the follower 31 may be of any preferred design, such as a pawl and ratchet arrangement 32 adapted to be actuated from the drive for the other parts of the machine. Conveniently the opposite sides of the label receptacle 30 are inclined at their forward ends as shown whereby the can after engaging the uppermost label will ride upwardly over the incline and out of pressing engagement with the remaining labels. The receptacle 30 has a cutout portion 33 conveniently adjacent the rear edge thereof, said cutout portion being adapted for the reception of the pasting mechanism for the lap ends of the labels and the curling device for the labels, and to permit of the withdrawal of said mechanism and device from the machine. The parts just mentioned will be presently referred to in detail.

Arranged between the opposite runways, and between the end of the label support or receptacle 30 and the delivery runway or chute 15 is a suitable presser pad 34, the feed belt 7 being adapted to coöperate with said presser pad 34 to press and fix the applied label to the can as the latter is released or discharged from the runway.

The pasting mechanism for the lap end of the label will now be described.

A suitable supporting bed or rest 35 is arranged to one side of the machine, conveniently the front side, the same having a relatively widened portion with longitudinally extending flanges 35^a adjacent opposite edges, and an elongated arm portion 35^b having at its outer end a spindle or stem 36 which latter is adapted to pass through an aperture in the adjacent side bar of the main frame 1, and which said spindle or stem terminates in an enlarged head or disk member 37 which latter is spaced from the inner side of the adjacent bar of the main frame 1. Sleeved upon the spindle 36 is a ratchet wheel 38, and pivoted to the main frame adjacent thereto as by a pivot bolt 39 is a locking dog 40 of any desired construction the latter being adapted to engage the serrations or ratchet portions of the wheel 38 and lock the latter in adjusted position. Conveniently integral with the wheel 38 is an elongated spool or bearing sleeve 41, while coiled about the latter and interposed between the disk or head 37 of

the spindle 36 and the ratchet wheel 38 is a suitable spring 42 which latter is secured at its respective ends to said disk 37 and ratchet wheel 38. From the construction just described it will be observed that the 70 arm 35^b with the widened bed or rest is adapted for pivotal or swinging movement about the bearing afforded by the aperture in the frame for the spindle 36 adjacent the end of said arm. The tendency of the 75 weighted end of the arm or support 35 is of course downwardly and the spring member 42, arranged as shown affords an adequate counterbalance or retarding device for regulating the said swinging movement. The 80 ratchet wheel 38 when engaged by the dog 40 constitutes in effect a fixed point of connection for one end of the spring, while the head or disk 37 connected to and movable with the arm 35^b constitutes a movable connection for the opposite end thereof. Now should it be desired to at any time adjust the tension of said spring 42 it is simply necessary to release the dog 40, when the ratchet wheel 38 which is sleeved upon the 90 spindle 36 may be rotated in either direction thereby increasing or diminishing the tension of the spring according to the direction of said movement.

The arm extension 35^b of the support or 95 rest 35 is conveniently provided with a downward projection 43 having a segmental slot 44 therein, which latter is designed to register with an aperture in the adjacent side wall of the frame 1. A pin 45 is arranged to loosely pass through the slotted portion 44 and preferably is threaded within the said aperture of the frame. This pin and slot engagement constitutes a guide for the swinging movement of the arm 35^b about 100 its pivotal connection, and also limits the movement thereof in either direction. A receptacle 46 adapted to contain paste or the like is designed to rest upon the bed or support 35 between the longitudinally extending flanges 35^a thereof, the said flanges engaging over opposite walls of the receptacle 46 constituting a support of the latter and guide ways for guiding the movement of the receptacle 46 longitudinally of the support 110 member 35. It is desirable to hold the receptacle 46 upon the support and against relative movement, after having been adjusted to proper position upon the rest or support 35, and to this end the bottom of the receptacle 46 is provided with a threaded aperture or recess 47 overlying a longitudinally extending slot 48 in the support or rest 35. A retaining bolt or the like 49 is designed to pass through the slot 48 and to have a 115 threaded engagement with the aperture or recess 47 in the base of the receptacle 46. At the lower end of the bolt 49 is an adjusting head 50 which underlies the slot 48 of the supporting bed or rest 35 and to securely 120

130

clamp the paste receptacle in position as is obvious. Secured to the wall of the paste receptacle in any desired manner as at 51 is an upright bracket 52 having an offset part 53 at the upper end thereof with oppositely disposed upright flanges 54 constituting therebetween a way for the reception of a lengthwise adjustable overhanging bracket arm or bar 55, which latter, when the pasting receptacle is in place upon the supporting bed 35, will be positioned over the labels supported within the receptacle 30, the said receptacle having a cutout portion 33 as before described for the reception of the overhanging arm or bar 55, and the parts carried thereby. The supporting arm 55 is provided with a longitudinally extending slot 56, and adapted to pass through said slot and engage a threaded aperture in the upright bracket 52. 10 20 30 40 50 60 70 80 90 broken surface, and one devoid of eyelets or openings usually employed for engagement with a sprocket or other drive. It has also been found in practice that the friction drive provided will effectively cause the continuous operation of the belt, and prevent slipping of the latter relative to the drive wheel 59, and the spring pressed pulley 67 will tend to stretch the endless carrier 60, and thereby maintain the same in taut condition. The pulleys 63 and 68 are conveniently made alike, and the peripheries thereof are annularly grooved as shown in detail in Fig. 12, which said grooves are adapted to accumulate paste from the endless carrier 60, which said accumulation of paste may be taken up by portions of the carrier which for any reason may use more of paste. A paste guard or shoe 79 provided with overhanging flanges 80 is slidably mounted upon both stretches of the belt 60, as shown, the said shoe having an overhanging lip 81 arranged to engage over the uppermost label in the label receptacle 30, adjacent the edge of the latter, and a downward projection 82 adapted to engage the edges of the labels. The purpose of this shoe is to guard the edges of the labels against the application of paste, as the endless carrier passes over the upper surface thereof. The shoe may be provided with a suitable longitudinally extending groove or grooves 83 for the accumulation of paste as the paste carrying member passes thereover whereby to guard against any portion of the belt being devoid of a sufficient quantity of paste. It is desirable to have means for adjusting the shoe upon the belt 60 whereby to bring the same into and out of engagement with the supported labels, without the necessity of smearing the hands with paste, and to this end novel adjusting means for the shoe is provided the same comprising an elongated arm or bar 84 pivoted to one side of the shoe 82 as at 85, the said bar passing through an aperture 86 in an angled projection 87 of a support 88 secured to the arm 55. In order to guide said arm 84, in its longitudinal adjustment and also to prevent rotary movement thereof and tilting of the shoe or guard 79, a guide wire or the like 89 is provided the same adapted to slidably engage the transverse recess in the terminal of the member 87, the wire 89 having offset ends 90 fitted within apertures in said arm 84. In this way the guard or shoe is prevented from tilting, the adjusting bar 84 is guided, and the movement of the latter is limited. The means for curling the labels is conveniently carried by the overhanging bar 55 and comprises a roll 91 conveniently corrugated as shown, the corrugations terminating short of the ends of the roll whereby to provide bearing studs 92 loosely sup-

ported in the bearings provided by the downwardly projecting offset portions or ears 93 on the oppositely disposed arms 94 of a substantially U-shaped supporting or carrying member 95. The carrying member 95 is conveniently pivoted as by a pivotal support 96 to the arm 55. A retaining nut 97 is threaded to the projecting end of the pivot rod 96 to prevent separation of the support 95 and retaining bolts are positioned upon the outer end of the curling roll 91 to prevent separation of the latter. When the paste receptacle 46 is properly positioned upon its support 35, the endless paste carrying member 60 will overlie the upper surface of the exposed label at the end thereof so as to apply a coating of paste to the lap ends of the label, and the curling roll 91 will engage said upper surface of the exposed label whereby as the label is drawn around the roll by the traveling can to which one end of the label is applied the free end of the label will be curled, so as to adjust itself to the periphery of the traveling can. By reason of the fact that the curling roll 91 is pivotally supported, it will be observed that the same may tilt or swing to accommodate itself to the position of the labels in the support, thereby resulting in a more effective curling of the same, and the corrugated arm, or roll has been found to be advantageous in the curling operation. It will also be noted that since the curling device and paste applying member are wholly supported upon the paste receptacle and to one side of the machine, these parts may be readily removed as desired, and also adjusted longitudinally of the machine whereby to properly position the parts relative to the supported labels.

A scraping mechanism for the endless pasting carrier is conveniently mounted upon the paste receptacle 46 and may take the form of a overhanging plate 99 secured to the top of the receptacle said plate having a recess 100 in one edge thereof adapted for the passage of the upper stretch of the endless paste carrier 60, an inclosing wall for the recess being provided by a substantially U-shaped yieldable packing 101 secured in position by a somewhat similarly constructed plate 102 secured in position as by bolts 103 and having downwardly projecting legs 104 which latter overlie the sides of the drive wheel 59 and afford a scraping means therefor. A wiper 105 is secured to the under surface of an adjustable plate 106 and projects forwardly beyond said plate as indicated in Fig. 3, so as to engage the belt 60 and wipe off any surplus paste. The plate 106 has an upwardly projecting finger piece 107, whereby the wiper 105 may be adjusted toward or from the belt 60. When adjusted, the plate 106 is held in position through the medium of a thumb screw 108.

The shaft 58 for the drive wheel 59 conveniently projects throughout the wall of the paste receptacle 46 for connection with the drive shaft 23. This connection is conveniently established by a flexible and extensible shaft connection comprising a tubular bar or shaft part 70 in which is adapted to slide a rod 71 having a jointed connection 72 with a coupling member 73 the latter being sleeved for the reception of a stud 74 projecting from the shaft 58 of the drive wheel 59, the said stud having a locking pin 75 adapted to engage within the inclined retaining slot 76 in the coupling member 73. A pin and slot connection 77 between the tubular member 70 and rod 71 provides a guide between these parts whereby they can be adjusted longitudinally relative to one another and prevented from separation. When desired to release the driving connection just described, it is only necessary to impart inward sliding movement to the rod 71, when the retaining pin 75 will ride out of the curved slot 76 and thus sever the connection between the parts 58 and 71. If desired a retaining hanger bracket 78 may be mounted upon the frame work of the machine, for supporting the shaft 70 and parts carried thereby when released from the shaft 58 carried by the paste receptacle.

The operation of the machine may be reviewed as follows: Motion having been imparted by the drive pulley 8 by any desired means the endless carrier 7 may be rotated and will take up and feed the cans along the runway 6, said cans having been previously spaced from one another as is usual. When brought into contact with the longitudinally extending roll 21 a film or coating of paste will be applied to the periphery of the can at the junction of the flange of the can top and the can body. Upon further movement of the can the same will engage the transversely extending roll 22 and receive a longitudinal daub of paste from said roll, it being noted that said rolls 21 and 22 receive their movement through the gear construction described from the driven shaft 12. The further movement of a can by the belt 7 brings the longitudinally pasted portion of said can to the forward or inclined end of the label receptacle 30, the pasted portion of the can engaging the forward end of the uppermost label and picking up the same in its rotary movement, when the label will be wound about the can, the lap end of the label being at the same time applied with a coating of paste through the medium of a cross/belt 60 and the winding action of the label being aided by the curling roll 91. The continued rotary movement of the can brings the same with the applied label upon the yieldable pressing support 34 which through the action of the belt 7 will press and affix the labels to the cans. It will be

noted that the labels when applied in the manner described will constitute a sealed joint between the cap and body thereby protecting the contents of the can.

- 5 It has before been suggested to provide an endless paste carrier adapted to apply a coating to the lap ends of the labels, but the present arrangement makes it possible to, with a great saving of time bodily 10 move the paste receptacle, the paste carrying member, the curling device, and their associated parts, and this without the necessity of first removing the paste belt or carrier from its support, since in the present instance both stretches of the belt travel above the label and are supported wholly to one side of the machine. Should it be desired to, at any time, adjust the position of the paste carrying member it is only necessary 15 to loosen, through the medium of the thumb piece 50, the retaining bolt 49 which plays in the slotted portion 48 of the portion 35 when the overhanging supporting arm 55, and the parts carried thereby, may be adjusted with the paste receptacle longitudinally of the machine upon the support 35. In this way the pasting member and curling device are adaptable to labels of different lengths, with the result that the pasting 20 member 60 will engage directly the lap end of the label regardless of its length. Should it be desired to take up or increase the play of the endless paste carrying member 60, it is only necessary to loosen the thumb screw 25 57 and slide the supporting arm 55 relatively to its seat 53 on the supporting bracket 52. Should it be desired to remove the paste receptacle and parts carried thereby which can be done from the side of the 30 machine, conveniently the front side, it is only necessary to lift the receptacle out of engagement with the flanges 35^a of the support 35 and draw the receptacle and associated parts outwardly, the coupling member 73 having previously been released from 35 connection with the shaft 58 of the drive wheel of the receptacle. The yieldable support for the receptacle provided by the 40 swinging arm 35^b and the connected spring 42 provides means whereby a constant and uniform pressure will be maintained upon the labels by both the paste applying member 60, and the curling device 91. The weight upon the free end of the supporting 45 arm 35^b caused by the paste receptacle and parts carried thereby will tend to cause said arm to drop by gravity into engagement with the labels, the spring connection 42 constituting in effect a counterbalance and 50 regulating the degree of pressure of said endless paste carrying member and curling device as is obvious. This pressure may be regulated at will by simply disengaging the locking dog 40 from the serrations of 55 the ratchet wheel 38 and turning the latter

in the desired direction upon the shaft 36, when the dog 40 upon being released will be forced by the spring 40' into locking engagement with said ratchet wheel 38, when the said ratchet wheel 38 will constitute a 70 fixed connection for one end of the spring, while the head 37 connected to the shaft or stud 36 constitutes a movable connection for the opposite end of said spring. The flexible construction of driving shaft for the 75 paste carrying member, constructed as described, permits of this tilting and swinging movement of the arm 35^b and the parts carried thereby without interfering with the continuous drive provided by said shaft. 80

What I claim is:

1. In a labeling machine, the combination of a label receptacle, a runway for cans or the like, means for feeding cans along the runway, a paste pot located to one side of the runway, a support mounted on the paste pot and projecting transversely across the label receptacle, and an endless paste carrying member having bearings on said support and paste pot respectively and movable 90 transversely across the labels in the receptacle.

2. In a labeling machine, the combination of pasting and labeling instrumentalities, a can runway or support, a paste carrying 95 member movable transversely of the machine and adapted to apply paste to the lap end of the labels; and a support for the paste applying member connected at a point below the runway and to one side of the machine, 100 the paste carrying member being removable with the support from the side of the machine.

3. In a labeling machine, the combination of a label receptacle, means for feeding cans 105 along the runway, a paste pot located to one side of the runway, a support mounted on the paste pot and projecting transversely across the label receptacle, an endless paste carrying member having bearings on said 110 support and paste pot respectively and movable transversely across the labels in the receptacle, the said paste pot being removable from the side of the machine, and said carrying member being removable with the 115 paste pot.

4. In a labeling machine, the combination of pasting and labeling instrumentalities, a can runway, means for feeding a can along the runway, an endless belt forming a paste 120 carrying member movable transversely across the machine adapted to apply paste to the lap end of the labels, and a detachable support for the belt positioned to one side of the machine and having an overhanging 125 arm arranged above the labels, the said belt being so supported that opposite stretches thereof will assume a position adjacent one another whereby to offer no obstruction above the runway.

5. In a labeling machine, the combination of a can runway, a label receptacle, a pasting receptacle detachably mounted upon one side of the machine, a paste carrying belt 5 adapted to move within said receptacle and transversely across the lap end of the supported labels, both stretches of the belt being adapted to move above the supported labels, and assume a position flat against the labels 10 whereby to permit cans to pass thereover.
6. In a labeling machine, the combination of a can runway or support, labeling instrumentalities, means for applying paste to the cans, and means for applying paste to the lap end of the labels, said last mentioned means comprising a paste receptacle, a paste carrying member movable within the receptacle and extending transversely across the machine, and a transversely extending 15 supporting bar above the runway for one end of said paste carrying member, said bar being adjustable.
7. In a labeling machine, a can runway or support, a label support, means for applying paste to the can, means for applying paste to the lap end of the labels, the latter comprising an endless belt the opposite stretches of which pass above the labels in the label support and transversely across the machine, 20 and means for supporting said paste carrying belt wholly from one side of the machine, whereby the same may be removed from said side of the machine.
8. In a labeling machine, a can runway or support, a label support, means for applying paste to the can, means for applying paste to the lap end of the label, the latter comprising an endless belt the opposite stretches of which pass above the labels in the label 25 support and extending transversely across the machine, and means for detachably supporting said paste carrying belt wholly to one side of the machine, the supporting means permitting opposite stretches of the belt to assume a flat position upon the labels 30 whereby to permit the cans to move thereover.
9. In a labeling machine, the combination of a runway or support for cans or the like, 35 a label receptacle, pasting appliances to one side of the receptacle, and pasting appliances adjacent the opposite side of the receptacle adapted to apply paste to the lap end of the labels, the last mentioned appliances comprising a paste receptacle, a drive wheel within the receptacle, a bracket arm secured to the receptacle and extending over the label support and having a pulley at its free end, and an endless paste carrier mounted upon the drive wheel and pulley whereby to position the paste carrier above the labels, 40 70 75
10. In a labeling machine, the combination of a runway or support for cans or the like, a label receptacle, pasting appliances to one side of the receptacle, and pasting ap-
- pliances adjacent the opposite side of the receptacle adapted to apply paste to the lap end of the labels, the last mentioned appliances comprising a paste receptacle, a drive wheel within the receptacle, a bracket arm 70 secured to the receptacle and extending over the label support and having a pulley at its free end, and an endless paste carrier mounted on the drive wheel and pulley whereby to position the paste carrier above the labels, 75 80
11. In a labeling machine, the combination of a runway or support for cans or the like, a label receptacle, pasting appliances to one side of the receptacle, and pasting appliances adjacent the opposite side of the receptacle adapted to apply paste to the lap end of the labels, the last mentioned appliances comprising a paste receptacle, a drive wheel within the receptacle, a bracket arm 80 85 secured to the receptacle and extending over the label support and having a pulley at its free end, and an endless paste carrier mounted upon the drive wheel and pulley whereby to position the paste carrier above the labels, 85 90
12. In a labeling machine, the combination of a can runway or support, a label receptacle, a paste carrying member for the lap end of the labels, a support for the latter connected at one side of the machine and having a part extending over the label receptacle, and free from connection at its outer end, said support permitting the paste carrying member to maintain a position flat against the labels whereby to permit the cans to pass thereover, 95 100 105
13. In a labeling machine, a can runway or support, a label receptacle, a paste receptacle, a drive wheel in the receptacle, a bracket arm mounted upon the receptacle and extending across the runway above the labels, said bracket arm having adjacent its outer free end a plurality of pulleys and an endless paste carrying member mounted at one end upon the drive wheel and at its outer end, upon the outermost pulley on the bracket arm whereby the paste carrying member is rotated, and opposite stretches of the paste carrying member being supported on the auxiliary pulley of the supporting arm, 110 115 120
14. In a labeling machine, a can runway or support, a label receptacle, a paste receptacle, a drive wheel in the receptacle, a bracket arm mounted upon the receptacle and extending across the runway above the labels, said bracket arm having adjacent its outer free end a plurality of pulleys and an endless paste carrying member mounted at one end upon the drive wheel and at its outer end upon the outermost pulley on the bracket 120 130

- arm whereby the paste carrying member is rotated, and opposite stretches of the paste carrying member being supported on the auxiliary pulley of the supporting arm, and 5 a pulley mounted upon the paste receptacle over which both stretches of the paste carrying members are adapted to move.
16. In a labeling machine, the combination of a can runway or support, a label receptacle, and pasting mechanism for the lap end of the label, said mechanism including an endless paste carrying belt extending transversely across the machine, a paste receptacle for the latter, and an adjustable 10 connection between the receptacle and the side of the machine whereby the paste carrying member may be adjusted longitudinally of the runway.
17. In a labeling machine, the combination of a can runway or support, a label receptacle, a paste receptacle, movable means mounted upon the receptacle and extending transversely across the receptacle for applying paste to the lap end of the label, means 15 for adjusting the paste receptacle longitudinally of the machine and relative to said label receptacle, and means whereby the receptacle with the paste member may be bodily removed from one side of the machine.
18. In a labeling machine, the combination of a can runway or support, label applying instrumentalities, a can feed, and means for applying paste to the lap end of the label comprising a paste receptacle sup- 20 ported at one side of the machine, an upright bracket arm on said receptacle, and a horizontal support on said bracket arm, a drive wheel mounted in the receptacle, a pulley at the end of the support, an endless paste 25 carrier mounted upon said drive wheel and pulley, and an auxiliary pulley having a grooved periphery, said pulley being mounted upon the horizontal support and adapted to support both stretches of the paste carrying member.
19. In a labeling machine, the combination of a can runway or support, label applying instrumentalities, a can feed, and means for applying paste to the lap end of the label comprising a paste receptacle sup- 30 ported at one side of the machine, an upright bracket arm on said receptacle, and a horizontal support on said bracket arm, a drive wheel mounted in the receptacle, a pulley at the end of the support, an endless paste 35 carrier mounted upon said drive wheel and pulley, and a scraper member carried by the receptacle for engaging the paste carrying member as it leaves the receptacle.
20. In a labeling machine, the combination of a can runway or support, a label applying instrumentalities, a can feed, and means for applying paste to the lap end of the label comprising a paste receptacle supported at one side of the machine, an upright bracket arm on said receptacle, and a horizontal support on said bracket arm, a drive wheel mounted in the receptacle, a pulley at the end of the support, an endless paste 40 carrier mounted upon said drive wheel and pulley, and a scraper member mounted upon the receptacle having an opening for the passage of the paste carrying member from the receptacle.
21. In a labeling machine, the combination of a runway and a holder for labels, means for applying paste to the labels comprising a paste receptacle, a paste applying means leading from the receptacle across the runway, and a support for said means having a supporting connection at one end only, and to one side of the machine.
22. In a labeling machine, the combination of a runway and a holder for labels, means for applying paste to the lap end of the labels comprising a paste receptacle, a paste applying means extending transversely across the receptacle and connected at one 45 end only to one side of the machine whereby it is fashioned for placement and removal across the runway from one side of the runway.
23. In a labeling machine, the combination of pasting and labeling instrumentalities, a can runway or support, a movable paste carrying member adapted to apply paste to the lap end of the labels, and a swinging support for the latter suitably supported for removal with the paste carrying member from the machine.
24. In a labeling machine, the combination of pasting and labeling instrumentalities, a can runway or support, a movable 50 paste carrying member adapted to apply paste to the lap end of the labels, and a yieldable support therefor positioned to one side of the machine and having an overhanging bracket arm arranged above the labels.
25. In a labeling machine, the combination of pasting and labeling instrumentalities, a can runway or support, a movable paste carrying member adapted to apply 55 paste to the lap end of the labels.

paste to the lap end of the labels, and a support therefor positioned to one side of the machine and having an overhanging arm arranged above the labels, said support being mounted for swinging movement.

26. In a labeling machine, a can runway or support, a label support, means for applying paste to the can, means for applying paste to the lap end of the label, the latter comprising an endless belt the opposite stretches of which pass above the labels in the label support, and means for supporting said paste carrying belt wholly to one side of the machine, said means permitting the belt to swing vertically.

27. In a labeling machine, a can runway or support, a label support, means for applying paste to the can, means for applying paste to the lap end of the label, the latter comprising an endless belt the opposite stretches of which pass above the labels in the label support, and means for supporting said paste carrying belt wholly to one side of the machine, said means permitting the belt to swing vertically and an associated counterbalancing means.

28. In a labeling machine, the combination of a can runway or support, a label receptacle, a paste carrying member for the lap end of the labels, a support for the latter connected at one side of the machine and having a part extending over the label receptacle, and free from connection at its outer end, said support being mounted for pivotal movement.

29. In a labeling machine, the combination of a can runway or support, a pasting mechanism arranged adjacent one end of the runway, a label receptacle, and an auxiliary pasting mechanism for the lap end of the labels, said mechanism including a paste receptacle, and an endless paste carrying belt, the receptacle and belt being removable together over one side of the machine, and a swinging support for the paste receptacle, and a yieldable retarding device associated therewith.

30. In a labeling machine, the combination of a runway and a holder for labels, means for applying paste to the labels comprising a paste receptacle, a paste applying means leading from the receptacle across the runway, and a support for said means having a yieldable connection at one end only with one side of the machine.

31. In a labeling machine, the combination of a runway and a holder for labels, means for applying paste to the labels comprising a paste receptacle, a paste applying means leading from the receptacle across the runway, a curling device for the label extending across the runway, and a support for said means and curling device having a supporting connection at one end only.

32. In a labeling machine, the combination of a runway and a holder for labels, means for applying paste to the labels comprising a paste receptacle, a paste applying means leading from the receptacle across the runway, and a curling device for the label extending across the runway, and a support for said means and curling device having a supporting connection at one end only.

33. In a labeling machine, a runway for cans or the like, a label support, a pivotally supported paste receptacle, a paste carrying member leading from the receptacle and adapted to move over the labels, said receptacle being mounted to move the paste carrier by gravity into contact with the labels.

34. In a labeling machine, a runway or support for cans or the like, a label support, a paste carrying member movable transversely across the machine, and a gravitating support for one end of the carrying member whereby the latter will exert a uniform pressure on the labels.

35. In a labeling machine, a runway or support for cans or the like, a label support, a paste carrier, a curling device, and a gravitating support for the carrier and device, whereby the same will exert uniform pressure on the labels.

36. In a labeling machine, a runway or support for cans or the like, a label support, a paste receptacle and a paste carrier, said receptacle and carrier being pivotally mounted for rocking movement whereby to contact the carrier with the labels.

37. In a labeling machine, a runway or support for cans or the like, a label support, a paste receptacle, a paste carrier and label curling device mounted upon the receptacle, the paste receptacle and parts carried thereby being mounted for bodily movement whereby to contact the pasting carrier and curling device with the labels.

38. In a labeling machine, a label receptacle, a runway or support for cans, a paste carrier, and a rock arm support for said carrier permitting contact with the labels, the same being held in contact by the weight of the support.

39. In a labeling machine, a label receptacle, a runway or support for cans, a paste carrier projecting transversely across the label receptacle, and a vertically movable pivoted support for said carrier permitting contact with the labels, the same being held in contact by the weight of the support and a retarding device for said support.

40. In a labeling machine, a label receptacle, a runway or support for cans, a paste carrier, and a yieldable swinging support for said carrier permitting contact with the labels, the same being held in contact by the weight of the support, and a yieldable retarding device for said support.

41. In a labeling machine, a can runway or support, a label receptacle, a paste carry-

ing member, a curling device for the labels, and a swinging support common to the paste carrier and curling device, permitting the said carrier and device to contact with 5 the labels by gravity.

42. In a labeling machine, a can runway or support, a paste receptacle, an endless paste carrier leading from the receptacle across the runway, an elongated support 10 extending longitudinally of the machine and pivoted to a stationary part thereof adjacent one end said support permitting the paste carrier to fall by gravity into contact with the supported labels.

15 43. In a labeling machine, a can runway or support, a paste receptacle, an endless paste carrier leading from the receptacle across the runway, a curling device operatively connected to the receptacle, an elongated support for the receptacle extending 20 longitudinally of the machine and pivoted to a stationary part thereof adjacent one end of said support permitting the paste carrier and curling device to fall by gravity 25 into contact with the support labels.

44. In a labeling machine, a can runway or support, a paste receptacle, an endless paste carrier leading from the receptacle across the runway, a curling device, a support 30 for the carrier and curling device, an elongated support for the last named support extending longitudinally of the machine and pivoted to a stationary part thereof adjacent one end permitting the 35 paste carrier and curling device to fall by gravity into contact with the supported labels, and a counterbalancing means for said support.

45. In a labeling machine, a can runway 40 or support, a paste receptacle, an endless paste carrier leading from the receptacle across the runway, a curling device, an elongated support extending longitudinally 45 of the machine and pivoted to a stationary part thereof adjacent one end of said support and having operative connection with the carrier and curling device, permitting the paste carrier and curling device to fall by gravity into contact with the supported 50 labels, and a spring retarding mechanism for said support.

46. In a labeling machine, a can runway, a label support having a suitable frame, an elongated arm pivoted at one end to the 55 frame and free at its opposite end, a paste receptacle mounted on the free end of the arm, and a paste feed leading from said receptacle across the runway of the machine and into contact with the supported labels.

60 47. In a labeling machine, a can runway, a label support having a suitable frame, an elongated arm pivoted at one end to the frame and free at its opposite end, a paste receptacle mounted on the free end of the

arm, and a paste feed leading from said receptacle across the runway of the machine and into contact with the supported labels and a curling device also mounted upon the paste receptacle for movement therewith. 65

48. In a labeling machine, a can runway, 70 a label support having a suitable frame, an elongated arm pivoted at one end to the frame and free at its opposite end, a paste receptacle mounted on the free end of the arm, and a paste feed leading from said 75 receptacle across the runway of the machine and into contact with the supported labels and an adjustable retarding device for said arm.

49. In a labeling machine, a can runway, 80 a label support having a suitable frame, an elongated arm pivoted at one end to the frame and free at its opposite end, a paste receptacle mounted on the free end of the arm, and a paste feed leading from said 85 receptacle across the runway of the machine and into contact with the supported labels and a curling device also mounted upon the paste receptacle for movement therewith, and an adjustable retarding device for said 90 arm.

50. In a labeling machine, a label receptacle, a can runway or support, a paste receptacle, an endless carrier leading from the receptacle and extending across the runway, 95 both stretches of the carrier being arranged above the label receptacle, and a friction drive mounted upon the receptacle for said carrier, said device being supported to one side only of the machine. 100

51. In a labeling machine, a label receptacle, a can runway or support, a paste receptacle, an endless carrier leading from the receptacle and extending across the runway, both stretches of the carrier being arranged above the label receptacle, and means 105 for imparting movement to said endless carrier comprising a drive wheel at one end of the carrier, and a guide pulley at the opposite end thereof and a yieldably supported 110 wheel mounted on the receptacle adapted to contact with both the endless carrier and said drive wheel.

52. In a labeling machine, a can runway or support, a label receptacle, a paste feeding means for engaging the labels supported on the receptacle, said paste feeding means extending across the receptacle, means for pivotally supporting the belt wholly to one side of the machine, and a flexible drive 115 mechanism for said paste feeding member permitting the latter to move about its pivoted connection.

53. In a labeling machine, a can runway or support, a label receptacle, a pasting 125 member adapted to be stretched across the runway, and a paste guard mounted upon said member for engaging the edge of the

- labels, and an adjusting member carried by said guard.
54. In a labeling machine, a can runway or support, a label receptacle, a pasting member adapted to be stretched across the runway, a paste guard mounted upon said member for engaging the edge of the labels, an adjusting member carried by said guard and a guide for said adjusting member.
55. In a labeling machine, the combination of a can runway or support, label pasting instrumentalities, and a curling device extending over the labels, said curling device comprising a corrugated roll.
56. In a labeling machine, the combination of a can runway or support, label pasting instrumentalities, and a curling device extending over the labels, said curling device comprising a corrugated rod mounted for pivotal movement.
57. In a labeling machine, the combination of a can runway or support, label pasting instrumentalities, and a curling device extending over the labels, said curling device comprising a rod having a pivotal connection substantially intermediate its ends.
58. In a labeling machine, the combination of a can runway or support, label pasting instrumentalities, and a curling device extending over the labels, said curling device comprising a pivotally supported substantially U-shaped arm, and a rod projecting between said arms.
59. In a labeling machine, the combination of a can runway or support, label pasting instrumentalities, and a curling device extending over the labels, said curling device comprising a pivotally supported substantially U-shaped arm, and a corrugated rod projecting between said arms.
60. In a labeling machine, the combination of a can runway or support, label pasting instrumentalities, and a curling device adapted to extend over the labels, said curling device comprising a lengthwise tilttable bar.
61. In a labeling machine, the combination of a can runway or support, label pasting instrumentalities, and a curling device adapted to extend over the labels, said curling device comprising a lengthwise tilttable bar and a movable support for the latter.
62. In a labeling machine, the combination of a can runway or support, label pasting instrumentalities, and a curling device adapted to extend over the labels, said curling device comprising a lengthwise tilttable bar and a swinging support for the latter.
63. In a labeling machine, the combination of pasting and labeling instrumentalities, a can runway or support, a movable paste carrying member adapted to apply paste to the lap end of the labels, and a support for the latter bodily removable with the paste carrying member from the machine, and a curling device for the labels also mounted on said support.
64. In a labeling machine, the combination of pasting and labeling instrumentalities, a can runway or support, a movable paste carrying member adapted to apply paste to the lap end of the labels, and a support for the latter bodily removable with the paste carrying member from the machine, and an automatically adjustable curling device for the labels also mounted on said support.
65. In a labeling machine, a can runway or support, a label support, means for applying paste to the can, means for applying paste to the lap end of the label, the latter comprising an endless belt the opposite stretches of which pass above the labels in the label support, means for supporting said paste carrying belt wholly to one side of the machine, and a curling device for the labels pivoted to said supporting means.
66. In a labeling machine, the combination of a runway or support for cans or the like, a label receptacle, pasting appliances to one side of the receptacle, and pasting appliances adjacent the opposite side of the receptacle adapted to apply paste to the lap ends of the labels, the last mentioned appliances comprising a paste receptacle, a drive wheel within the receptacle, a bracket arm secured to the receptacle and extending over the label support and having a pulley at its free end, and an endless paste carrier mounted over the drive wheel and pulley whereby to position the paste carrier above the labels, said bracket arm being adjustable, and a curling device also mounted on said bracket arm.
67. In a labeling machine, the combination of a runway or support for cans or the like, a label receptacle, pasting appliances to one side of the receptacle, and pasting appliances adjacent the opposite side of the receptacle adapted to apply paste to the lap ends of the labels, the last mentioned appliances comprising a paste receptacle, a drive wheel within the receptacle, a bracket arm secured to the receptacle and extending over the label support and having a pulley at its free end, and an endless paste carrier mounted upon the drive wheel and pulley whereby to position the paste carrier above the labels, and a spring pressed guide pulley mounted upon the receptacle for said paste carrying member arranged in substantial alignment with the pulley upon the bracket arm.
68. In a labeling machine, the combination of a can runway or support, a label receptacle, a paste carrying member for the

lap ends of the labels, a support for the latter connected at one side of the machine and having a part extending over the label receptacle, and free from connection at its outer end, and a paste guard or shoe slidably connected with said support, and adapted to engage the edges of the labels.

69. In a labeling machine, the combination of a can runway or support, a label receptacle, a paste carrying member for the lap ends of the labels, a support for the latter connection at one side of the machine and having a part extending over the label receptacle, and free from connection at its outer end, and a paste guard or shoe slidably connected with said support, and adapted to engage the edges of the labels, said shoe having a part projecting beyond said support and constituting an adjusting handle.

70. In a labeling machine, the combination of pasting and labeling instrumentalities, a can runway or support, a movable paste carrying member adapted to apply paste to the lap ends of the labels, and a yieldable support therefor positioned to one side of the machine and having an overhanging bracket arm arranged above the labels, and a curling device for the labels mounted on said support.

71. In a labeling machine, the combination of a can runway or support, a label receptacle, a paste carrying member for the lap ends of the labels, a support for the latter connected at one side of the machine and having a part extending over the label receptacle, and free from connection at its outer end, said support being mounted for pivotal movement, and a curling device movably mounted on said support.

72. In a labeling machine, the combination of a can runway or support, a label receptacle, a paste carrying member for the lap ends of the labels, a support for the latter connected at one side of the machine and having a part extending over the label receptacle, and free from connection at its outer end, said support being mounted for pivotal movement, a curling device movably mounted on said support, and a paste shoe slidably mounted on said paste carrying member and having an adjusting part slidably connected to said support.

73. In a labeling machine, the combination of a can runway or support, a label receptacle, a paste carrying member for the lap ends of the labels, a support for the latter connected at one side of the machine and having a part extending over the label receptacle, and free from connection at its outer end, said support being mounted for pivotal movement, and a flexible driving mechanism for the paste carrying member

permitting the pivotal adjustment of the support.

74. In a labeling machine, a runway for cans or the like, a label support, a paste receptacle, a paste carrying member leading from the receptacle and adapted to move over the labels, said receptacle being connected to a rock arm mounted to move the paste carrier by gravity into contact with the labels, and a flexible drive for said paste carrier permitting said adjustment of the paste carrier while maintaining the driving connection with the latter.

75. In a labeling machine, the combination of pasting and labeling instrumentalities, a can runway or support, a movable paste carrying member adapted to apply paste to the lap end of the labels, a paste receptacle for said paste carrying member constituting a supporting means for the latter, said paste receptacle being mounted wholly to one side of the machine and having a removable and pivotal connection with the machine, and a flexible and detachable drive connection for said paste carrying member, permitting the latter to be adjusted or removed at will.

76. In a labeling machine, a runway for cans or the like, a label support, a paste receptacle positioned to the side of the machine, a bracket arm extending from the receptacle and projected across the machine, a paste carrying member leading from the receptacle and supported by said arm, and means whereby said paste carrier moves by gravity into contact with the labels.

77. In a labeling machine a runway for cans or the like, a label support, an elongated paste applying member movable transversely across the machine and in the path of the supported labels, an elongated pivotal support for said paste carrying member, having associated means permitting the carrier to act with uniform pressure upon the labels.

78. In a labeling machine, a can runway or support, a paste carrier movable across the machine, a support for the paste carrier, a curling device operatively connected to the support for the paste carrier, and said support having a pivotal connection at one end to the side of the machine.

79. In a labeling machine, a can runway, a label receptacle, a support positioned to one side of the machine and having an arm projecting across the label receptacle, paste applying means supported on said arm, and a curling device also supported on said arm.

80. In a labeling machine, a can runway, a label receptacle, a support positioned to one side of the machine and having an arm projecting across the label receptacle, paste applying means supported on said arm, a

curling device also supported on said arm, and means whereby said arm positions the paste applying means by gravity.

81. In a labeling machine, a can runway, a label receptacle, a support positioned to one side of the machine and having an arm projecting across the label receptacle, paste applying means supported on said arm, a curling device also supported on said arm,

means whereby said arm positions the paste applying means by gravity, and a yieldable retarding means for the gravity control.

In testimony whereof I affix my signature in presence of two witnesses.

FREDERICK H. KNAPP.
